UNITED STATES PATENT OFFICE.

SAMSON WILLIAMSON, OF SEATTLE, WASHINGTON.

CLOTHES-DRIER.

1,109,890.

Specification of Letters Patent. Patented Sept. 8, 1914.

Application filed November 18, 1912. Serial No. 732,020.

To all whom it may concern:

Be it known that I, SAMSON WILLIAMSON, a citizen of the United States, residing at Seattle, in the county of King and State of Washington, have invented certain new and useful Improvements in Clothes-Driers, of which the following is a specification.

This invention relates to that class of foldable clothes driers which are adapted to be secured to a wall and be elevated after the clothes have been hung on the drier arms.

The object of the invention is the perfecting of devices of this character to render the same less expensive in construction, which will be convenient to manipulate and efficient in operation.

The invention consists in certain improvements in clothes driers which, together with their several advantages, I shall hereinafter describe with reference to the accompanying drawings, in which—

Figure 1 is a front elevation of a clothes-drier embodying my improvements and with the arms folded. Fig. 2 is a vertical sectional view with the arms extended. Fig. 3 is a plan view of the drier with the arms in the positions in which they are illustrated in Fig. 2. Fig. 4 is a plan view of the spider member of the drier, shown detached.

Referring to the drawings, the numeral 5 represents a board or an equivalent, which is rigidly secured to the wall or other suitable support, as by means of screws 6. Adjacent to the upper and lower ends of said board are attachments 7 and 8 which serve with the board as sockets for an upright pole 9. Said board and sockets constitute what may be deemed the frame of the drier.

Rigidly secured to the upper end of pole 9 is a sector-shaped head 10, see Fig. 3, formed with a web 11 and an arcuate rim 12 which depends therefrom by radially disposed bars 14. These bars are spaced to afford intervening openings 15 of widths to accommodate the arms 16 upon which the clothes are hung. The distance between the upper surface of said rim and the under surface of the web is equal, approximately, to the thickness of the arms at their inner ends.

The reference numeral 17 represents a spider provided with a sleeve 18 which is adapted to be freely moved up or down upon the pole 9 and when the pole is mount-

ed on the support 5, the spider will be disposed above the upper end thereof and the socket 7. The spider is also formed with an arcuate element 18' and protruding from the latter are radial lugs 19, as best shown in Fig. 4.

The lugs 19 are directed upwardly and are apertured for the reception of a wire 20 which is threaded therethrough and likewise through holes provided adjacent to the inner ends of the arms to serve as pivotal connection for the same with respect to the spider lugs, between which the arms are located.

The pole 9 is provided with spaced holes, as 21, 21¹, and 21² for the reception of a removable pin 22 which is utilized for retaining the pole at selected heights by inserting the pin into the proper hole and immediately above one of the attachments 7 or 8 and whereby the pin is supported.

23 represents a pull rod connected at its upper end to the spider and is desirably formed with a loop 24 at its lower end to afford a handle for actuating the same.

The operation of the invention is as follows: When the device is unemployed, the various parts occupy the positions in which they are shown in Fig. 1. By withdrawing the pin 22 and pulling down the pole 9 the head 10 is correspondingly moved while downward movement of the spider is prevented through the obstruction of the attachment 7. The head being thus lowered into proximity of the spider causes the arms to be swung outwardly until they are extended into nearly horizontal positions, as represented by full lines in Fig. 2, and then being supported upon the head-rim 12. The clothes are then hung upon the arms 16, whereupon the pole is pushed upwardly to elevate the various parts connected therewith into the positions indicated by broken lines in Fig. 2 and are thus held by inserting the pin 22 into one of the holes in the pole and above one attachment 7 or 8. The arms 16 are held in a horizontal position by their own weight and the weight of the clothes hanging thereon, said arms at their inner ends as at 20, having a tendency to be forced upwardly to engage the head 10.

When the clothes are dried, they are removed from the arms after the pole has been again lowered. To fold the arms, the pull-rod 23 is grasped in one hand and firmly held while the pole 9 is pushed up-

wardly with the other hand, and thereby restoring the device into the condition in which it is shown in Fig. 1.

The clothes rack constructed as above explained takes up but little room, is constructed of relatively few parts which are unlikely to become deranged, is readily opened or closed and may be hung with clothes at a convenient height and then raised to subject them to the relatively hotter atmosphere found in proximity to the ceiling of a room.

What I claim is—

In a clothes-drier, the combination of a wall board, a pair of spaced vertically aligned sockets secured thereto adjacent the upper and lower ends thereof, a pole rectangular in cross section slidably mounted in said sockets for vertical movements and having its inner face contacting the wall board, said pole provided with a series of spaced openings, a pin adapted to be selectively inserted in one of said openings and resting upon the upper edge of the lower socket for holding the pole at a pre-

determined height with respect to the wall board, a head fixedly secured to the upper end of the pole and provided with a plurality of openings disposed between upper and lower elements of the head, the length of the upper elements being greater than that of the lower elements, a spider having a rectangular sleeve slidably mounted on said pole, upwardly and outwardly extending lugs carried by said spider, a pull rod connected to said spider and arms hingedly connected to the lugs and extending through the respective openings in said head whereby when the pole is lowered the spider will engage the upper socket and the arms will be extended and be supported upon the lower element of said head while the inner ends of said arms engage the upper elements of said head.

Signed at Seattle, Wash., this 30th day of October, 1912.

SAMSON WILLIAMSON.
